UNITED STATES PATENT OFFICE.

JAMES B. McCARTHY, OF BIRMINGHAM, MICHIGAN, ASSIGNOR TO NATIONAL METAL MOLDING COMPANY, OF PITTSBURGH, PENNSYLVANIA, A CORPORATION OF PENNSYLVANIA.

INSULATOR WALL-BRACKET.

1,225,460.

Specification of Letters Patent.

Patented May 8, 1917.

Application filed March 31, 1916. Serial No. 82,024.

To all whom it may concern:

Be it known that I, JAMES B. McCARTHY, residing at Birmingham, in the county of Oakland and State of Michigan, a citizen of the United States, have invented or discovered certain new and useful Improvements in Insulator Wall-Brackets, of which improvement the following is a specification.

My invention relates to insulator brackets such, for example, as are attached to the outer walls of buildings and form supports for electrical conductors leading from street mains into buildings. However, I do not wish to be understood as limiting my invention to this specific purpose, for the improved bracket which I provide is well adapted to be used as a support for electrical conductors within buildings, on poles, and in various other places.

The object of my invention is to provide a bracket, which although strong, durable and efficient, is small, inexpensive to manufacture, and inconspicuous when installed. A further object is to improve the construction of insulators, both with respect to the means for fastening conductors to them, and for attaching the insulators to supports.

In the accompanying sheet of drawings, which forms part of my specification, I have illustrated the preferred embodiment of my invention. Figure 1 is a face view of a bracket; Fig. 2 is a sectional view taken on the line II-II, Fig. 1; and Figs. 3 and 4 are views similar to the left hand portion of Fig. 2, but showing modifications of construction.

The bracket which I provide comprises essentially a supporting member adapted to be attached to a wall or other desired structure, and insulators detachably connected to such member. As shown in the drawings, the supporting member is preferably an elongate plate 1, rounded at its ends, and provided with a reinforcing rib in the form of a continuous rim or flange 2. The plate is further provided with a series of holes or slots 3 adapted to receive suitable securing members for attaching the bracket to any desired structure, as for example, to the outer wall of a building.

As far as concerns some features of my invention the insulator may be of any desired shape or construction and may be attached to the supporting member in various ways. Preferably, however, I provide an

insulator such as shown in the drawings and connect it to the supporting member in the manner there indicated. The insulators at the opposite ends of support in Figs. 1 and 2 are identical in form, but, in their attachment to the support, the securing members are placed at right angles to each other. As shown in these figures, the body portion 4 of each insulator is substantially cylindrical having suitable grooves 5 for the attachment of electrical conductors. To the end that such conductors may not become disconnected, the insulator is provided with a transverse hole 7 extending substantially through the center or axis thereof, and through which the wires or conductors may be threaded. It will be observed that, by the provision of a hole 7 in the manner described, conductors may be securely attached to the insulator quite regardless of the angle at which the conductor leads to or from the insulator; that is to say, a conductor may approach or leave the insulator in line with the longitudinal axis thereof, or at any angle thereto, and, being passed through the hole 7, may be firmly attached to the insulator. As will be seen, grooves 13 are formed in the upper part of the insulator adjacent to the ends of the hole 7, such grooves being for the purpose of receiving conductors leading to or from the insulator at other than right angles thereto.

At opposite sides of the hole 7 there are longitudinally disposed holes 8 adapted to receive a U-bolt 9 or some other form of attaching member. As shown in Fig. 2, the legs of the U-bolt extend through suitably provided holes in the plate 1, and nuts 10, screwed upon such legs, hold the insulator firmly in place. It will be observed of this construction that the flange 2 of the plate is of sufficient depth to extend beyond the ends of the U-bolt.

In the modification shown in Fig. 3 the U-bolt 9^a is inserted from the back of the plate 1 and a suitable yoke or clamping plate 11 is placed over the ends of the bolt and between the nuts 10^a and the insulator body 4^a.

In the modification of Fig. 4 the base of the bracket 1^a is provided with threaded holes 12 adapted to be engaged by screws 15, which in turn extend through a suitable yoke plate 11^a.

According to the provision of the patent

statutes, I have described the principles and operation of my invention together with the construction which I now consider to be the best embodiment thereof. However, I desire to have it understood that the construction shown is only illustrative and that my invention may be practised by other forms of construction.

I claim as my invention:

- 10 1. An insulator bracket, comprising a supporting member provided with holes for attaching an insulator thereto, an insulator provided with a wire-receiving hole extending substantially transversely through the axis thereof and further provided with a pair of longitudinally disposed holes lying one on each side of said first named hole, an annular groove in the outer surface of said insulator, and an attaching member 15 extending through said pair of holes in the insulator and through said holes of the supporting member, said attaching member clamping the inner end of the insulator to said supporting member.
- 25 2. An insulator wall bracket for the attachment and support of electrical conductors, comprising in combination a supporting member provided with means for attaching an insulator thereto, a unitary substantially cylindrical insulator provided 30 with an open wire-receiving hole extending substantially transversely through the axis

thereof, and further provided with a pair of longitudinally disposed holes lying one on each side of said first named hole, an annular groove in the outer surface of said insulator in the general plane of said transverse hole, and an attaching member extending through said pair of holes in the insulator and engaging said supporting member and 40 clamping the insulator to said member.

3. An insulator bracket, comprising a supporting member provided with holes for attaching an insulator thereto, an insulator provided with a wire-receiving hole extending substantially transversely through the axis thereof and further provided with a pair of longitudinally disposed holes lying one on each side of said first named hole, an annular groove in the outer surface of said insulator and longitudinally disposed grooves extending from said annular groove to the outer end of the insulator, and an attaching member extending through said pair of holes in the insulator and through 50 said holes of the supporting member, said attaching member clamping the inner end of the insulator to said supporting member.

In testimony whereof I have hereunto set my hand.

JAMES B. McCARTHY.
